COMBINED LAMP AND RADIO

Yoshikazu Imanishi, Osaka, Japan, assignor to Imanishi
Flexible Tube Mfg. Co., Ltd., Osaka, Japan, a corpo-
ration of Japan

Filed Oct. 24, 1966, Ser. No. 4,390

Claims priority, application Japan June 6, 1966

Term of patent 14 years

(Cl. D48—20)

FIG. 1

FIG. 4

FIG. 2

FIG. 3

FIG. 1 is a top plan view of the combined lamp and radio of the present invention;

FIG. 2 is a front elevation view of said combined lamp and radio;

FIG. 3 is a side elevation view taken from the right side of said combined lamp and radio; and

FIG. 4 is a rear elevation view of said combined lamp and radio.

I claim:

The ornamental design for a combined lamp and radio, as shown.
